CLOSURE CAP AND PACKAGE

William P. White, Glencoe, Ill., assignor to White Cap Company, Chicago, Ill., a corporation of Delaware

Application January 2, 1936, Serial No. 57,119

6 Claims. (Cl. 215—7)

This invention relates generally to packaging, and pertains particularly to an improved package and closure therefor, adapted for the packaging of liquids and other commodities.

A primary object of the invention is the provision of a package having a removable closure or stopper, of tamper-proof character, in that the stopper or closure cannot be removed without showing plainly that it has been, and certain features of the closure are permanently destroyed incident to its removal, thereby preventing its re-use in the original condition, although permitting the continued use of the closure as an effective stopper for the container.

Another object is the provision of such a closure which will form an hermetic seal on an appropriate container, and which is not subject to deterioration with age or from contact with the packaged material.

Yet another object is the provision of such a closure which may be manufactured economically, applied to the container with facility, and removed without requiring the use of a special implement.

Yet another object is the provision of such a closure which is neat and ornamental in appearance and which may be manipulated with facility in removing it from and re-applying it to the container.

Other and further objects will be pointed out or indicated hereinafter, or will be apparent upon an understanding of the invention or its employment in use.

For the purpose of making clear the nature of the invention, I show in the accompanying drawing forming a part of this specification, and hereinafter describe, one form of closure cap embodying the invention, but it is to be understood, however, that this is presented merely for purpose of illustration and that the invention may be availed of in other and modified forms without departing from the scope of the appended claims.

In said drawing

Fig. 1 is an elevational view, partly in section, illustrating a closure cap adapted for use on a bottle or the like;

Fig. 2 is a bottom view of same;

Fig. 3 is an elevational view, partly in section, of a sealing cap constituting an element of the structure illustrated in Fig. 1;

Fig. 4 is a bottom view of a holding member constituting an element of the structure illustrated in Fig. 1;

Fig. 5 is a sectional elevation of the upper portion of a package comprising a container with

a closure of the construction illustrated in Fig. 1 secured thereto;

Fig. 6 is a sectional elevation corresponding to Fig. 5 and showing the relationship of the closure and container after the former has been detached from the latter as in process of being removed from or replaced on the container; and

Fig. 7 is a sectional elevation of a modified form of closure embodying the invention.

For the packaging of liquors or other commodities it is frequently desirable to employ a package of such character that it may be immediately ascertained whether or not it has been opened. It is quite desirable that the closure or stopper for the container be of such character that it may be continued in use, after its initial removal, to form an effective closure for the container, and that it be susceptible of subsequent re-application and removal to permit dispensing of portions of the packaged contents from time to time. Heretofore various devices intended to serve this purpose have been provided, same including a stopper, of cork or the like, and a sheath which envelops the cork and is secured to the container, such sheath being severable more or less readily to permit access to the stopper for removal thereof. Such devices do not adequately fulfill their purpose due to the fact that the sheaths are of relatively simple character and separable from the stopper, thus permitting the package to be restored to its original and unopened appearance simply by the application of a new sheath to the container and the original stopper.

The present invention provides a closure in which the sealing element is of distinctive character and is permanently a part of the sheath which has to be mutilated in the opening of the package in the first instance. Thus the closure is entirely incapacitated for re-application to the container in simulation of the original unopened condition of the package, although it may be continued in use as an effective closure for the container.

The nature of the invention will be more fully ascertained from a detailed understanding of the embodiment illustrated in the drawing, which will now be described.

As seen in Fig. 1, the closure comprises a sheath member 10, a sealing closure 11 having a sleeve gasket 12 therein, and a holding member 14. The sealing closure, which is illustrated in Fig. 3, comprises a cap or shell formed of a suitably strong resilient sheet metal having an interior coating of a suitable lacquer or other material which will effectively resist the action of the

- material which is to be packaged. This shell has a top panel 15, which is domed upwardly in its central part, and a peripheral skirt or flange portion depending from the top panel, the lower portion 16 of said skirt or flange flaring outwardly and the upper portion 17 being substantially cylindrical or otherwise formed on a smaller diameter than the flaring portion 16. The lower marginal portion of the skirt is turned inwardly to 10 form a flange 18 which covers the lower edge of the gasket 12.

The gasket 12 is of sleeve form and is made of a suitable soft but strongly elastic material, such as rubber. It is held under circumferential 15 striction or compression by the skirt of the shell, so that it conforms to the contour thereof in the flaring portion 16, extending somewhat above the lower limit of the holding portion 17 but having its upper margin spaced from the top panel 15.

20 The sheath 10 is formed of a softer or more readily severable material such as light sheet aluminum. It is considerably deeper than the shell of the sealing closure 11 and is of internal diameter such as to receive the same snugly. It 25 has a top portion 20 from which depends an annular skirt, said skirt being formed with flutes 21 which extend for the greater portion of its depth from the top portion, leaving the lower portion 23 in cylindrical form. The inwardly 30 offset portions of said flutes terminate at sloping surfaces 22 which are inclined inwardly and upwardly at the same angle as the flaring portion 16 of the sealing closure.

35 The holding member 14 is in the form of a flat metal plate of generally circular outline and of size such as to be received within the sheath 10, and is provided with projections 24 adapted to interengage with portions of the flutes 21, whereby the member 14 is held against rotation within 40 the sheath. Preliminary to insertion of the holding member into the sheath, a drop of solder 25 is applied to the central portion of its under surface.

In assembling the closure from the parts above 45 described, the sheath is placed in inverted position, the holding member 14 is inserted into the sheath so that it comes to rest against the inner surface of the sheath top, and the sealing closure 11 is then inserted into the sheath until its domed 50 top portion comes into contact with the drop of solder 25. Heat is then applied to the domed portion over the drop of solder, fusing the latter and soldering the sealing closure shell to the holding member 14.

55 The sheath is then subjected to a punching or slotting operation by which portions of its skirt adjacent the marginal flange 18 of the sealing closure shell are partially severed and bent inwardly against and across said flange 18, forming 60 retaining elements 26 which serve to clamp the sealing closure securely and permanently in the sheathing member, with the flaring portion 16 in abutment with the sloping portions 22 and the holding member 14 in abutment with the 65 sheath top 20.

This forms in the skirt of the sheath a series of apertures 27 running circumferentially thereof at an appropriate distance above its lower margin. Said apertures are separated by narrow 70 strands 28 of the sheath metal, which strands constitute the sole remaining connection between the cylindrical lower portion of the sheath skirt and the fluted upper portion in which the sealing closure is permanently secured.

75 The closure is thus in condition for applica-

tion to an appropriate container, to form the complete package.

The container 29, which may be a bottle or other suitable vessel, has at its mouth a rigid annular wall formed with a substantially cylindrical peripheral sealing surface 30 which is of a diameter somewhat smaller than the internal diameter of the holding portion 17 and the flange 18 of the sealing closure and the lower margin of the gasket 12, but substantially larger than the 10 internal diameter of the balance of the constricted gasket 12. The container is also provided with a peripheral ledge 31 which is of a diameter such as to fit within the lower cylindrical portion 23 of the closure sheath. This ledge 31 is spaced 15 from the mouth rim of the container by a distance which slightly exceeds the depth of the sealing closure skirt.

After the container has received its contents the closure is placed upon its mouth, the mouth 20 rim entering slightly within the lowermost flaring portion of the gasket 12. Downward pressure is then applied to the top of the closure, forcing it to seated position on the container, in which position the lower limit of the sealing closure 25 shell is slightly above the ledge 31 and the top panel 15 is in contact with the mouth rim of the container, as seen in Fig. 5. In this forcing of the closure to seated position, the pressure applied to the top of the sheath is transmitted directly to the top of the sealing closure shell, and also, through the medium of the flutes 21, to the flaring portion 16 of the sealing closure shell. The downward movement of the closure relative to the container causes a wedging action to be 35 exerted upon the elastic gasket, causing it to be elongated upwardly along the holding portion 17 and placing it under high compression between said portion and the sealing surface 30 of the container. Thus a strong hermetic seal is 40 formed between the container and the closure.

Such seating of the closure upon the container brings the lower margin of the sheath skirt to a position somewhat below the peripheral ledge 31, and the lower portion of the sheath skirt is then 45 spun or flanged inwardly under the ledge, thus locking the closure to the container. The package is thus hermetically sealed and cannot be opened without obvious mutilation.

In order to open the package, the narrow 50 strands 28 are severed, as with a knife or other thin object. Since these strands occupy a position between flange 18 and the ledge 31, the severing of them is easily accomplished by inward pressure, and the severed margins are bent inwardly against the upper surface of the ledge 31 and the lower surface of the flange 18, as seen in Fig. 6. After the strands 28 are severed, the package may be opened by giving the closure a 55 rotary and upward movement. The removal 60 may be assisted, if need be, by prying upwardly on the flange 18, using the ledge 31 as a fulcrum for the prying object.

After having been thus removed, the sealing 65 closure remains permanently connected with the sheath, and may be re-applied by pressing it down onto the mouth of the container, where the compression of the gasket holds it securely in place. Re-application and subsequent removal of the 70 closure are facilitated by giving it a rotary movement, and this manipulation is facilitated by the depth and fluting of the sheath. In such operation the sealing closure is positively held against 75 rotation in the sheath due to the interengagement

of the holding member 14 with the flutes of the latter.

In the modified form of closure shown in Fig. 7 the sheath is designated generally by the reference numeral 10'. The sheath skirt is originally formed with two outside diameters, the upper portion of the sheath skirt being formed with the inwardly offset flutings 21' as above described, and the lower portion originally being on a larger radius as shown in dotted lines at 23' and being united with the upper portion by an annular offset portion 31. At its lower margin the skirt of the sealing cap is formed with an outwardly extending fold 32 of a diameter such as to be received within the lower portion 23' of the skirt and bear upon the offset portion 31 when the top of the sealing cap is in abutment with the holding member 14'.

In the form shown in this figure, the top of the sealing cap is flat, not domed as in the form above described, and the holding member is dished so that the central portion will abut the flat top of the sealing cap when the upper margin of the peripheral flange 40 of the holding member is in abutment with the top of the sheath. Thus flange 40 aligns with the upper skirt portion 11a of the sealing cap, forming a strut through which downward pressure may be transmitted from the top of the sheath to the sealing cap. The flange 40 is provided with the outwardly extending projections 24' which engage between the flutings 21' of the sheath, for the purpose above described, and the holding member is fixedly secured to the sealing cap as above described. It will be apparent that this flat-topped form of sealing cap and dished holding member may be used in the form of sheath illustrated in Fig. 1.

After the sealing cap has thus been positioned in the sheath, the lower portion 23' of the latter is bent inwardly under the outwardly extending fold 32 of the sealing cap to clamp the fold against the offset portion 31. The lower portion 23' of the sheath is retained in cylindrical form, as shown in the full line position in Fig. 7, and is punched at intervals, as above described, to form the retaining elements 26' which are bent inwardly into contact with the marginal flange 18' of the sealing cap. Such punching forms the narrow severable elements as above described. This modified form of closure is applied and affixed to the container as above described, and is operable for removal and re-application in the manner above described.

What I claim is:

1. A closure for packing containers comprising, in combination, a sheath having a top portion and depending peripheral skirt, a sealing cap housed in the sheath and having a top portion and a peripheral skirt depending therefrom, which cap skirt has an outwardly projecting portion, said sheath having inwardly projecting portions

engaging the skirt of the sealing cap to retain the latter permanently in the sheath, said sheath skirt also being formed with inwardly offset flutings extending from its top portion downwardly into overlying engagement with the outwardly extending portion of the cap skirt, the lower portion of the sheath skirt being adapted to be telescoped onto and bent into retentive engagement with a container, said lower portion of the sheath skirt being connected with the balance thereof by narrow readily severable portions spaced from one another circumferentially of the sheath.

2. A closure for packing containers comprising, in combination, a sealing closure having a top portion and a downwardly extending sealing element of elastic sealing material, a sheath housing said sealing closure, said sheath including a depending peripheral skirt having inwardly extending portions engaging the sealing closure to retain it in the sheath, a lower portion of said sheath skirt being adapted to be telescoped onto and bent into retentive engagement with a packing container, said lower portion of the sheath skirt being connected to the balance thereof by narrow severable portions spaced from one another circumferentially of the sheath, and a holding member fixedly connected with the sealing closure and having engagement with the sheath effective to prevent rotation of the sheath relative to the sealing closure.

3. A closure as specified in claim 2 and wherein the sheath skirt has inwardly offset portions and said holding member has interfitting engagement with said offset portions.

4. A closure for packing containers comprising, in combination, a sealing cap having a top portion and depending peripheral skirt, a sheath housing said sealing cap and including a peripheral skirt having inwardly bent portions engaging under the lower margin of said cap skirt to retain said sealing cap permanently in the sheath, said sheath having inwardly offset portions above said inwardly bent portions, and a holding member fixedly connected with the sealing cap and engaging said inwardly offset portions of the sheath to hold the sheath against rotation relative to the sealing cap.

5. A closure as specified in claim 4 and wherein the holding member is of dished form and is interposed between the top of the sealing cap and the top of the sheath and includes an annular flange extending from the top of the sheath to the top of the sealing cap for transmitting pressure from the former to the latter.

6. A closure as specified in claim 4 and wherein the holding member comprises a plate disposed in abutment with the top of the sheath, and the top of the sealing cap is domed upwardly into abutment with the holding member.

WILLIAM P. WHITE.
